(57) **CLAIM**

The ornamental design for a compaction cleat assembly, as shown and described.

DESCRIPTION

FIG. 1 is a perspective view of a compaction cleat assembly in accordance with an embodiment of the present invention.

FIG. 2 is a side elevational view thereof;

FIG. 3 is an end elevational view thereof;

FIG. 4 is a top plan view thereof;

FIG. 5 is a bottom plan view thereof;

FIG. 6 is a cross-sectional view thereof taken along line 6-6 of FIG. 4.

FIG. 7 is a perspective view of the base portion of the compaction cleat assembly of FIG. 1 shown in unassembled condition for ease of illustration.

FIG. 8 is a side elevational view thereof;

FIG. 9 is an end elevational view thereof;

FIG. 10 is a top plan view thereof;

FIG. 11 is a bottom plan view thereof;

FIG. 12 is a cross-sectional view thereof taken along line 12-12 of FIG. 10.

FIG. 13 is a perspective view of the cleat cap portion of the compaction cleat assembly of FIG. 1 shown in unassembled condition for ease of illustration.

FIG. 14 is a side elevational view thereof;

FIG. 15 is an end elevational view thereof;

FIG. 16 is a top plan view thereof;

FIG. 17 is a bottom plan view thereof;

FIG. 18 is a cross-sectional view thereof taken along line 18-18 of FIG. 16; and,

FIG. 19 is an exploded perspective view of the compaction cleat assembly of FIG. 1.

Any broken lines shown in all figures are for illustrative purposes only and form no part of the claimed design.

1 Claim, 10 Drawing Sheets
